Primary Examiner — Manpreet Matharu*Assistant Examiner* — Aula Soroush(74) Attorney, Agent, or Firm — Maier & Maier, PLLC(57) CLAIM

The ornamental design for a set of shirt sleeves, as shown and described.

DESCRIPTION

FIG. 1 is a front view of a set of shirt sleeves, showing my new design;

FIG. 2 is a rear view thereof;

FIG. 3 is a left side elevation view thereof;

FIG. 4 is a right side elevation view thereof;

FIG. 5 is a right side elevation view of the left sleeve; and, FIG. 6 is a left side elevation view of the right sleeve.

The broken lines shown in the drawings illustrate environmental subject matter only and form no part of the claimed design. The dashed-dot lines shown in FIGS. 1, 2, 5 and 6 illustrate a boundary and form no part of the claimed design.

1 Claim, 4 Drawing Sheets(56)
